D. GASSNER,

Cook Stove.

Patented July 11, 1838.

David Staford of New York City

Inventor's Patent, dated July 11, 1855.

The Schedule referred to in the following Patent and making part of the same, containing a description in the words of the inventor, and claiming his improvement in the construction of coal cooking stoves.

To all to whom these presents shall come, I do, & know that at David Staford of the City, County and State of New York, have invented a new and valuable improvement in Coal Cooking Stoves, and that the following is a full and exact description of the construction and operation of the said Improvement as invented by me. — The improved coal cooking stove as herein claimed by the subscriber is particularly adapted for burning anthracite coal, and may be constructed of steel or iron as follows.

The grate which is of a recess form is placed in the center of the stove, its bars, extending horizontally and somewhat raised from front to back, it is suspended at each side by a horizontal movable bar upon which it rests as a hinge or pivot. One or both of these bars may be withdrawn when it is necessary to clean or repair the grate. These bars are attached to the stove, one of which is placed at each side the grate and elevated sufficiently near it to admit the heat underneath. These spaces for admitting the heat are at the sides of each oven, between the front and back plates of the stove. The backs of the ovens are shielded with fire brick 4 inches perpendicular to the sides of the grate, thus leaving a span of the width of the grate between them, this which the smoke and heat passes to the chimney above. The top or upper plate of the stove is made a certain height above the ovens and is perforated to admit briars.

The advantage claimed by this method of construction is a steady and uniform degree of heat which may be applied to all parts of the stove at the same time. — The subscriber claims the privilege of manufacturing his improved coal cooking stove of any shape or dimensions.
